Primary Examiner — Sheryl Lane*Assistant Examiner* — Emily A Caven(74) *Attorney, Agent, or Firm* — Bayramoglu Law Offices LLC(57) **CLAIM**

The ornamental design for a dog expelling device, as shown and described.

DESCRIPTION

FIG. 1 is a front, bottom and left perspective view of a dog expelling device showing my new design;

FIG. 2 is a front view thereof;

FIG. 3 is a rear view thereof;

FIG. 4 is a left side view thereof, a right side view being a mirror image of the left side view;

FIG. 5 is a bottom view thereof;

FIG. 6 is a top view; and,

FIG. 7 is a rear, top and right perspective view thereof. The broken lines depict portions of the dog expelling device that form no part of the claimed design.

1 Claim, 7 Drawing Sheets(56)
